UNITED STATES PATENT OFFICE.

FLOYD E. WHITLATCH, OF MUSKOGEE, OKLAHOMA.

BOTTOM MARGINAL SIGNAL FOR TYPEWRITERS.

Application filed October 25, 1921. Serial No. 510,299.

To all whom it may concern:

Be it known that I, FLOYD E. WHITLATCH, a citizen of the United States, residing at Muskogee, in the county of Muskogee and 5 State of Oklahoma, have invented certain new and useful Improvements in Bottom Marginal Signals for Typewriters; and I do hereby declare the following to be a full, clear, and exact description of the same, 10 reference being had to the accompanying drawings, forming part of this specification.

This invention relates to a device for use on typewriters for indicating to the operator that the sheet being written upon has 15 been typed to the predetermined bottom margin, thus permitting the operator to preserve a uniform bottom margin on all the sheets.

The object of the present invention is to 20 produce a device of this nature that will be set by a feeler mechanism or detector of delicate touch and operated by the rugged carriage return and line spacing mechanism.

A further object of the present invention 25 is to produce a warning device that may be adjusted to produce a signal at a previously chosen distance from the bottom of a sheet of paper without respect to the length of the paper.

30 Other various objects of the present invention are set forth in the claims, among others being the provision of an audible signal produced during the operation of the line shifting mechanism and repeated at the close of such operation; the provision of a sharp, clear and loud signal upon reaching a definite margin at the bottom of the paper, this being possible by reason of the fact that the feeler mechanism for determining 35 the position of the sheet of paper does not in itself operate the bell but merely causes a change in position of other mechanism which in turn controls the operation of the bell; and the provision of a feeler mechanism sufficiently delicate to detect the passage of the bottom of a sheet of very thin paper.

One of the great advantages in the present 40 device is due to the fact that the mechanism can be installed on a standard typewriter

without any radical change in the present construction, the added parts being so designed that they can be secured to the end wall of the typewriter carriage frame without in any way affecting the operation of 55 any of the present mechanisms.

Typists who are particular about their work frequently criticize the lack of provision in the now standard type of front strike visible typewriters of means for preserving a uniform bottom margin. In the old style machine it was possible to raise the carriage and see exactly how much space was left, and it was also possible to scratch a mark on one of the paper-holding fingers 60 so that a uniform bottom margin could be had, but since in the visible typewriters the platen is movable only in the direction of its longitudinal axis, except in some machines for shifting, it is impossible to see the location of the bottom of the paper.

Aside from the great advantage in neatness, it is a great convenience for even an ordinary typist to know when she approaches the bottom of the sheet of paper 75 and to be able to tell how much writing space remains as at times the operator will write on the very edge itself absolutely ruining the appearance of the page.

In the present invention means are provided for actuating a signal, here an audible one illustrated as a gong, at a predetermined time so as to notify the operator of the typewriter that the last line to be written on the sheet has been completed, thus eliminating 85 the requirement that the operator must watch the position of the paper and also insuring an absolute even margin at the bottom of the page of such width as to give the page a neat appearance.

80 In a device of this nature there are two main requirements; one, that the margin selector shall be adjustable so that when the left hand margin is made small the bottom margin may be shortened preserving the 90 neatness of the page, and the other that the signal shall be one to control attention. If the gong were controlled directly by the feeler or detector the sound would necessarily be very weak so that it is essential in 100

order to have a practical device that the detector be delicately poised and operate only some intermediate link in the mechanism, leaving the operation of the bell to mechanism requiring no delicacy of touch.

In the present invention both of these objects are well taken care of, the ringing of the gong being caused by the hand operated carriage return lever which not only returns the carriage to the right hand side of the machine when the end of the line has been reached, but also causes the rotation of the platen of the typewriter into position to type a new line. The detector mechanism is on the opposite side of the metal side piece of the carriage frame and is delicately poised by an extremely weak spring, this mechanism serving merely to advance or retract a tiny slide not in contact with any mechanism when it moves, but which later serves to elevate a trip rod causing such rod to assume an inoperative position when the detector is held in writing position by the presence of a sheet of paper on the platen.

It should be particularly noted that not only is the sound of the gong in the present invention loud and clear, but that it is struck at a time when the operator is not engaged in writing, the first sound or sounds being struck at the beginning of the line shifting operation and the second sound or sounds being struck immediately after the close of the carriage shifting stroke, each of these two or four signals being given between the writing of what should be the last line and the bringing of the mechanism into position to write the next line. A further and important advantage of the present mechanism is that, should the operator deliberately ignore this repeated warning and rewrite a further line the warning will be repeated twice at the close of each succeeding line.

In the drawings,

Figure 1 is a plan view of my device in its preferred form;

Fig. 2 is a side elevation viewed from the left hand end of the typewriter;

Fig. 3 is a side elevation of the mechanism as viewed from the platen or inner side;

Fig. 4 is a front elevation showing the device after a sheet of paper has been inserted in the typewriter;

Fig. 5 is a similar view showing the position of the mechanism after the bottom of the paper has passed the feeler or detector here shown as a roller;

Fig. 6 is an elevation showing the trip rod about to be raised;

Fig. 7 is a sectional elevation taken on the broken line 7-7 of Fig. 3;

Fig. 8 is an elevation of the slide in signal causing position;

Fig. 9 is a similar view, but showing the slide in manifolding position.

Figs. 10 and 11 are views showing the bell-ringing mechanism.

While this device is capable of being placed upon any standard visible typewriting machine, for convenience of illustration I have shown a single embodiment of the invention as I have applied it to an Underwood typewriter. The platen 10 is of the standard type with the single exception that I have cut a shallow groove 11 near the left hand edge slightly beyond the position corresponding to zero on the scale. This platen is journaled as usual in the triangular metal end 14 of the carriage frame and is revolved about its axis by the hand wheel 15 or by the usual carriage return lever 18 pivoted to the carriage frame as at 19, this lever, as is customary, performing the two functions of causing the return of the typewriter to the right by its striking against the edge of the slot covered by the nickel cap plate 20, and also causing the rotation of the platen by shifting the carrier arm 22 to which is pivoted the pawl 23 which operates the ratchet wheel 25 secured to the platen shaft.

The mechanism of the present invention is all located near and is carried by the end 14 of the carriage frame and consists generally in three parts, namely; the detector mechanism carried on the underside of the frame, the reciprocating and bell-ringing mechanism carried on the outside of the frame, and the small slide which forms the connecting link between the two sets of mechanism just mentioned.

On the carrier arm 22 which is reciprocated by the carriage return lever 18, against the tension of a spring 27 connected to the pin 28 on the carrier arm and a similar pin 29 on the end 14, is pivoted a trip rod 31 carrying at its free end a trip 32. This trip rod is held at its front end by its pivot and its movement at its free end is limited in an upward direction by engagement with the end 14 and is limited in downward extent by engagement with a pin 34 carried by the carrier arm 22, this pin 34 resting in a slot in the trip rod 31 when the latter is in its lowermost position. The rear upper surface of the trip rod 31 lies in a plane parallel with the bottom surface of the end 14 when the trip rod is raised. The bottom surface of the trip rod is provided with a curved recess 36 so as to clear the slide 38 except when the carrier arm 22 is being reciprocated.

With the slide 38 in the position shown in Fig. 2, in which position the mechanism would be when no paper is in the machine, the trip rod 31 is reciprocated with the carrier arm 22 and the trip 32 moves in a horizontal plane in which is also located the cusped projecting tongue 39 extending from the swinging trigger plate 40 which is piv-

oted to the bracket 41 and carries the angular wire 42 which forms the shaft of the hammer 43.

At each stroke of the carrier rod 22 the 5 trip 32 engages the curved edge of the tongue 39 and with a cam-like movement causes the trigger plate 40 to swing about its pivot 45 in the lugs 46 extending from the bracket 41 and causes the hammer 43 to 10 rise and strike the top of the gong 47. As the trip 32 passes the tongue 39 the latter will drop by gravity and will cause the striking of a sound blow of the hammer on the gong.

15 When the carriage has been moved to the right the lever 18 is released and as the carrier bar 22 moves forward the trip 32 again engages the double curved tongue 39 and causes the hammer to strike the gong once 20 above and once below its center as before upon completion of the oscillation of the carriage return lever, thus giving four separate strokes of the gong to each complete movement of the lever 18.

25 With the slide 38 in the position shown in Fig. 6 the rearward movement of the carrier arm 22 brings the edge of the recess 36 in the trip rod 31 into engagement with the slide and since this rod is free to move upward it rises out of contact with the headed pin 34 thus moving the trip 32 into a plane not in the path of the tongue 39. With the slide in this position, therefore, the gong is not sounded, but at the completion of each 35 shifting of the platen by the lever 18 the slide 38 is entirely out of contact with any of the parts so far described, lying within the recess 36, but out of contact with the walls thereof.

40 The slide 38 is a small piece of sheet metal having an outer end 52 and a lower and larger end 53, the former being cut away to provide a shoulder 54 for engagement by the hinged plate 55 which controls the movement of this slide. The slide is located within and held in position by a guide 56 having channeled ends 57 and 58, the guide being fastened to a small projection 60 forming part of the standard Underwood typewriter and which has a notch 61 in its upper edge for the purpose of guiding the sheet metal carrier arm 22. At its inner end, that is, the end nearest the platen, the slide 38 carries a relatively weak curved spring 53 63 which rests in all positions against the peripheral edge of the hinged plate 55.

In the position shown in Fig. 8 the detector 64 is within the groove 11 in the platen. The spring is now in its most expanded position and the slide is in its outer position and held in such position by contact of the hinged plate 55 with the shoulder 54. In Fig. 4 the spring 63 is somewhat compressed, a number of sheets of paper being 53 in the machine. In this view the slide is

at the inner limit of its travel with the shoulder 65 in contact with the carrier bar 22. In Fig. 9 the slide is in exactly the same position as in Fig. 4, but since the typewriter is now being used for manifolding the detector 64 is held at some little distance from the platen and the spring 63 is now compressed still further.

It will thus be seen that the presence of even the thinnest sheet of tissue paper between the platen 10 and the indicator roller 64 will cause movement of the slide, and that the amount of paper in the machine has no effect on the position of the slide, the irregularity in the size or amount of paper being taken care of by the resilience of the spring 63.

The mechanism for controlling the position of the slide 38 will now be described. On the inner face of the end wall 14 of the typewriter carriage frame is secured, by means of screws 66 or other fastenings, a base plate 67 having a flanged collar 68 serving as a pivotal mounting for the rotary disk 69 as best seen in Fig. 7.

The base plate 67 is provided with an arcuate portion 71 having therein a plurality of holes 72 all equi-distant from the center of the base plate 67, this point being in the axis of the platen. The upturned ends 73 of the arcuate portion 71 serve as stops to engage the indicator extension 74 of the rotary disk 69, this extension being somewhat resilient and having a locking pin 75 adapted to engage any one of the holes 72, holding the rotary disk 69 and the relatively stationary base plate 67 in the desired relation to one another.

At its lower end the rotary disk 69 has an extension 76 provided with upturned lugs 77 perforated to receive a pivot 78 of the hinged plate 55, this latter plate having lugs 81 and being held in place against the rotary disk 69 by means of a spring 82 coiled about the pivot rod 78 and engaging the hinged plate 55 at its center and having its ends secured in a pair of hooks 85 rising from the extension 76.

In addition to an arcuate portion 86 adapted to engage the free end of the spring 63 the swinging plate 55 carries a relatively long arm 88 in which is pivoted the detector roller 64. The extensions 89 on the arm 88 serve as paper guides directing the paper 90 between the roller 64 and the platen 10.

When no paper is in the machine the roller 64 rests within the groove 11 and the swinging plate 55 is held by its weak spring 82 against the collar 68 of the base plate 67, the power of the spring 82 being sufficiently great, however, to hold the slide 38 at its outward limit of travel, in which position the trip rod 31 rides in lower and bell-ringing position.

When paper is between the platen and the

roller or detector 64 the swinging plate 55 is moved against the force of the spring 82 into the position shown in Fig. 4 or between that position and the position shown in Fig. 9, in either event the slide being at its inner limit of travel and the swinging plate 55 being turned about its pivot 78 and out of contact with the collar 68. In this position the trip rod 31 rides at the higher level and the trip 32 is therefore restricted to a path above and out of contact with the tongue 39 which controls the hammer 43 of the gong.

What I claim is:

1. In a device of the character described, a platen, a carrier arm, a pawl thereon for revolving said platen, signal mechanism, and means carried by said carrier arm for operating said signal mechanism upon each reciprocation of said carrier arm.

2. In a device of the character described, a platen, line spacing mechanism, signal mechanism, a trip carried by said line spacing mechanism for operating said signal mechanism, and means governed by the bottom of the paper being written upon for positioning said trip mechanism.

3. In a bottom margin signalling device, a platen, signal mechanism, means for rendering said signal mechanism inoperative, a detector mechanism operatively connected thereto, and means for adjusting said detector mechanism about the periphery of the platen.

4. In a bottom margin signalling device for typewriters, a platen, a line spacing reciprocating member, means carried thereby for revolving said platen, an audible signal device, means carried by said reciprocating member for operating said audible signal, means for detecting the passage of the bottom of a sheet of paper past a predetermined point, and means cooperating with the means carried by said reciprocating member for rendering same inoperative until after passage of the bottom of the sheet past said predetermined point.

5. In a device of the character described, a detector, and means for causing a warning to be given, after passage of a sheet of paper past said detector, immediately before and also immediately after return movement of the carriage.

6. In a device of the character described, a detector, and means for causing a warning consisting of a plurality of audible sounds to be given, after passage of a sheet of paper past said detector, immediately before and also immediately after return movement of the carriage.

7. In a device of the character described, a signal mechanism controlled by the location of the bottom edge of the sheet of paper, a reciprocating trip, and means moving transversely to the movement of said trip

for guiding said trip into and out of a path where it would contact with and operate said signal mechanism.

8. In a device of the character described, a platen, a detector, a sliding guide controlled by said detector, signal mechanism, and means controlled by the relative position of the bottom of the paper and the detector for sliding said guide to render inoperative said signaling mechanism.

9. In a device of the character described, a detector, trip positioning means operated by said detector, signal mechanism and trip mechanism for operating said signal mechanism and adapted to deflect said positioning mechanism until a predetermined margin from the bottom is reached so that until such time said signal mechanism shall be inoperative.

10. In a device of the character described, a signal mechanism for indicating the passage of the bottom of a sheet of paper being written upon past a predetermined point, and means pivoted concentrically with the axis of the platen for altering at will said predetermined point.

11. In a device of the character described, a pivoted bell hammer, a reciprocating member, an arcuate cam on said hammer and lying in the path of said member, a detector, and means operated by said detector for raising said member above said cam.

12. In a device of the character described, a pivoted bell hammer, a reciprocating member, an arcuate cam on said hammer and lying in the path of said member, a detector, a slide movable transversely of said member to raise same above said cam, and means for operatively connecting said detector and slide.

13. In a device of the character described, a detector, a bell, and means for ringing said bell twice on each forward and each backward movement of the line space lever after passage of a sheet of paper past said detector.

14. In a device of the character described, a plate pivotally mounted with the platen, a hinged member carried by said plate, a detector carried by said member, and an alarm mechanism controlling slide operated by said hinged member.

15. In a device of the character described, a plate pivotally mounted concentric with the platen, means for locking said plate at any desired angular relation with respect to the carriage frame, a detector pivoted to said plate; a signal mechanism, and means operatively connecting said mechanism to said detector.

16. In a device of the character described, a plate pivotally mounted concentric with the platen, means for locking said plate against pivotal movement, pivotally mounted detector mechanism carried by said plate,

a freely moving guide, a spring on one end of said guide and in the path of pivotal movement of said detector mechanism.

17. In a device of the character described, a plate pivotally mounted concentric with respect to the platen, a member hinged to said plate, a detector carried by said mem-

ber, a slide adapted to be moved in one direction by said member, and a spring lying in the path of said member as it is moved about its hinge as a pivot by contact of the detector with paper upon the platen.

FLOYD E. WHITLATCH.
